UNITED STATES PATENT OFFICE.

FREDRIK LJUNGSTRÖM, OF LIDINGÖ-BREVIK, SWEDEN, ASSIGNOR TO AKTIEBOLAGET LJUNGSTRÖMS ANGTURBIN, OF STOCKHOLM, SWEDEN, A CORPORATION.

REVERSIBLE TOOTHED GEARING FOR LOCOMOTIVES.

Application filed August 3, 1922. Serial No. 579,549.

To all whom it may concern:

Be it known that I, FREDRIK LJUNGSTRÖM, a subject of the King of Sweden, residing at Lidingö-Brevik, Sweden, have invented certain new and useful Improvements in Reversible Toothed Gearing for Locomotives, of which the following is a specification.

In locomotives it has been previously suggested to provide a mechanical power transmitting mechanism between the driving engine and the driving wheels, and in the case of the driving engine consisting of a turbine it is well known that this mechanical power transmitting mechanism comprises spur wheels. Because of the load gauge limiting in each separate case the extension of the toothed gearing particularly in lateral direction and consequently in axial direction, it has proved difficult to so construct the toothed gearing that the reversing may be effected by inserting an extra toothed wheel adapted for backward running. It has previously been suggested to insert such an extra reversing wheel between two other radially displaceable wheels which may be moved radially apart by one of the wheels being supported by a frame work adapted to be raised and lowered about a point situated outside the toothed gearing. This reversing device is particularly suited to toothed gearings from which the movement is transmitted to the driving wheels through coupling rods, the lay shaft possibly existing in such case being adapted to be raised and lowered. This invention relates to a reversing device which may be used also in toothed gearings of the type in which the movement is transmitted from the toothed gearing to a pair of driving wheels without the use of coupling rods. The invention relates more particularly to a reversing device in toothed gearings appertaining to locomotives and containing spur wheels and consists chiefly in two shafts movable radially and journaled eccentrically, one of said shafts supporting one or more extra toothed wheels intended for backward running, the other shaft supporting one or more toothed wheels intended for forward running, all of said toothed wheels being brought, upon the radial adjustment of the shafts, into or out of engagement with each other and with one or more other toothed wheels in the toothed gearing.

Two embodiments of the invention are il-

lustrated in the accompanying drawings. Figs. 1, 2 and 3 are a vertical section, a side view and a horizontal section respectively of an embodiment of the toothed gearing, Fig. 1 showing a section on the line A—B—C 60 in Fig. 2 and Fig. 3 a section on the line E—E in Fig. 2. Figs. 4, 5 and 6 show similar views of another embodiment, Fig. 4 shows a section on line F—G—H in Fig. 5 and Fig. 6 a section on line K—K in Fig. 5.

Referring to the drawings, 1 designates the driving engine which in this case is a turbine actuating by means of its shaft 2 and the toothed wheels 4 secured to the same, the toothed wheels 6 secured to a shaft 5. Mounted on the shaft 5 are also toothed wheels 7 actuating the toothed wheels 8 attached to another shaft 9. By the toothed wheels 10 secured to the shaft 9, said wheels being a little smaller than the toothed wheels 8, the movement is transmitted through the toothed wheel 11 and the diaphragms 13 in well-known manner to the driving shaft 3 and, if desired, from the latter by means of coupling rods 14 to other driving wheels.

As shown in the drawing the toothed gearing is adjusted for forward running. Backward running is effected by extra toothed wheels 17 and 18 being inserted 85 between the toothed wheels 8 and 11, said toothed wheels 17 and 18 being adapted, after the toothed wheels 10 and 11 by radial displacement of the shaft 9 are brought out of engagement with each other, to be 90 thrown in between the toothed wheels 8 and 11. The toothed wheels 17 and 18 are secured to a shaft 19 which is journaled eccentrically by means of the eccentric 20, said wheels being adapted to be brought 95 into engagement with the toothed wheels 11 and 8 by the center of the shaft 19 having been moved from the position designated by 21 to the position designated by 22. The shaft 9 to which the toothed wheels 100 8 and 10 are secured is journaled eccentrically by means of the eccentric 23 in such manner that the center of the shaft may be displaced from the position 24 to the position 25 in which latter the toothed 105 wheels 10 and 11 are brought out of engagement with each other. Since the positions 24 and 25 are at equal distance from the center 26 of the shaft 5, the toothed 110 wheels 8 and 7 remain always in engage-

ment with each other. The radial movement of the shaft 9 is effected by means of the eccentric 23, the lever 27 being reversed to such a position that the center of the shaft 9 corresponds to the position 25. By reversing the lever 28 the shaft 19 is then displaced to the position 22 and on account thereof the toothed wheel 8 is brought into engagement with the toothed wheel 18 and the toothed wheel 17 into engagement with the toothed wheel 11. Thus the driving wheel shaft 3 is caused to run backwards in relation to the direction of movement obtained by the movement being transmitted directly from the toothed wheel 10 to the toothed wheel 11.

In the embodiment shown in Figs. 4 to 6 the reversing device is located in another place of the gearing than that described above. According to the invention the shaft 5 is so journaled by means of the eccentric 30 that the shaft may be moved radially from the position 31 to the position 32, the extra toothed wheel 33 intended for backward running and secured to shaft 41 being adapted by means of the eccentric 35 to be moved from the position 36 to the position 37 by raising or lowering the levers 39 and 40 respectively. As the positions 31 and 32 are at equal distance from the center 38 of the turbine shaft 2, the toothed wheels 4 and 6 are always in engagement with each other during this movement. If the shaft 5 be moved from the position 31 to the position 32, the toothed wheels 7 and 8 are brought out of engagement with each other, and the extra toothed wheel 33 intended for backward running is then, by reversing the lever 39, moved from the position 37 to the position 36 and thrown in between the toothed wheels 7 and 8. In this case only one reversing wheel is needed, which wheel, if the gearing contains spiral cut toothed wheels, has to be provided with teeth crossing each other in well-known manner.

By the aid of a reversing device constructed according to the invention backward running may be effected by throwing in or out toothed wheels having the least possible movement, which is necessary in case of large toothed gearings in which the operation is effected by means of oil under pressure, the different levers being connected with oil cylinders. As in many cases the reversing of the direction of movement has

to be affected very rapidly, a great accuracy is necessary in such an operation by means of oil, such accuracy being most readily obtained by small movements of the movable parts, while at the same time a great consumption of oil does not jeopardize the high pressure on the oil necessary in each separate case.

What I claim as new and desire to secure by the Letters Patent of the United States is:—

1. In a reversible gearing for locomotives in combination, a driving shaft, a driven shaft and an intermediate shaft, a pair of eccentrically mounted additional intermediate shafts, pairs of spiral cut gears on each of said shafts and arranged to mesh with correspondingly cut gears on the adjacent shafts, means for moving one of the eccentrically mounted shafts radially to establish a forward motion and a three stage reduction, means for moving the other eccentrically mounted intermediate shaft subsequent to disengaging of the first mentioned eccentrically mounted shaft from one of the first mentioned shafts so that the second mentioned eccentric shaft will engage the first mentioned eccentrically mounted shaft and the shaft from which the first eccentrically mounted shaft has previously been disengaged to effect reversible movement of the gearing.

2. A reversible gearing as claimed in claim 1, wherein two pairs of gear wheels are mounted on the eccentrically mounted and radially movable shafts and on two of the three first mentioned shafts and are provided with oppositely inclined spiral cut teeth, one pair of said gear wheels on the forward running eccentrically mounted shaft being in engagement with the only pair of gear wheels on the remaining first mentioned shaft during forward running while on reversing the other pair of gear wheels on the same shaft is engaged with a corresponding pair of gear wheels on the second mentioned eccentrically mounted shaft, and the remaining pair of gear wheels on the second mentioned eccentrically mounted shaft are engaged with the same single pair of gears of the said first mentioned shaft during the said reverse movement of the gearing.

In testimony whereof I affix my signature.

FREDRIK LJUNGSTRÖM.
